UNITED STATES PATENT OFFICE.

BURNHAM C. STICKNEY, OF ELIZABETH, NEW JERSEY, ASSIGNOR TO UNDERWOOD COMPUTING MACHINE COMPANY, OF NEW YORK, N. Y., A CORPORATION OF NEW YORK.

COMBINED TYPEWRITING AND COMPUTING MACHINE.

1,356,232.

Specification of Letters Patent.

Patented Oct. 19, 1920.

Application filed March 29, 1919. Serial No. 286,014.

To all whom it may concern:

Be it known that I, BURNHAM C. STICKNEY, a citizen of the United States, residing in Elizabeth, in the county of Union and State of New Jersey, have invented certain new and useful Improvements in Combined Typewriting and Computing Machines, of which the following is a specification.

This invention relates to computing machines, and is herein disclosed as applied to a combined typewriting and computing machine of the Underwood-Hanson type, wherein the numeral keys of the typewriter set up pins or indexing devices corresponding to the digits written as the carriage travels along, so that the digits represented thereby can be later carried into the numeral wheels. The mechanism as herein disclosed also includes one form of the complementary subtraction devices used in said machines.

In machines of that type, it is desired for some purposes to have the numbers printed in one form when added, and in another form when subtracted, thus enabling anyone inspecting the typewritten work-sheet to ascertain at once whether the digits written therein were added or subtracted. In order to enable the written-out work-sheet to thus indicate the character of the work, the device may be such that when the typewriter carriage enters the zone in which subtraction, for example, is to be effected, the typewriting mechanism should be locked or rendered inoperative unless subtraction is as a matter of fact effected. The connections for effecting this should preferably cover the whole of the subtraction zone. Since such machines, however, are sometimes used for writing other than computed digits in any column, the device should not print the digits in a manner to indicate subtraction unless deliberately made to do so.

With these and other advantages in mind, the ordinary Underwood-Hanson machine is modified, so that when the carriage enters a given zone the usual column-stop may be utilized as a means for compelling the typewriting to be effected in the upper case for example. The column-stop may exercise this control throughout that zone. The device may be released from the control of the tabulating stop when the typewriter carriage passes out of this zone, preferably by

having the stop engaged throughout the zone with a cam whose length is substantially identical with that of the zone.

In order to release the setting of the typewriter-controlling devices, they may be connected to be released at the actuation of the general operator in a manner analogous to that sometimes used for releasing a subtraction setting. In order to permit the operation of the ordinary typewriter keys at the computing zone, the computing keys may be the only keys adapted to be locked in such zone, thus making it unnecessary to alter the character of the typewriting unless numerals are actually being written. The key for disconnecting or silencing the computing devices may also make the locking devices ineffective, so far as controlled by the computing mechanism. The connections therefore may be such that it is the setting to subtraction which changes the character of typewriting, and that such changing is unnecessary unless computing is actually effected.

Other features and advantages will hereinafter appear.

In the accompanying drawings,

Figure 1 is a sectional side view, largely diagrammatic, of an Underwood-Hanson combined typewriting and computing machine, showing my invention as applied thereto, with the parts set for normal writing.

Fig. 2 is a view similar to Fig. 1, but taken nearer the center, showing the keys locked, with most of the other parts omitted.

Fig. 3 is a view similar to Fig. 1, but taken nearer the center, with many of the parts omitted, and showing the mechanism set for subtraction, unlocked and writing in upper case.

Fig. 4 is a perspective view of the "5" numeral-key type-bar, showing the two kinds of types upon it.

Fig. 5 is a perspective rear view of the tabulator casing, showing the cam which cooperates with the column-stop.

Fig. 6 is a skeleton perspective view, showing the typewriting connections when writing outside of a computing zone.

In the Underwood-Hanson machine, alphabet keys 10 and numeral keys 11, when depressed, carry down key-levers 12 and 13 to swing sub-levers 14, so that each sub-

lever 14 will swing its type-bar 15 upwardly and rearwardly, causing lower-case type 16 to print on the front side of the usual platen 17. The platen 17 is journaled, as usual, by means of its axle 18 in a shift frame 19 mounted in a carriage 20, which normally tends to travel to the left under the tension of a spring drum 21, but which is normally held by means of the usual dog 22 engaging 10 the escapement wheel 23.

Whenever a type-bar 15 rises, its heel 24 strikes a universal bar 25, moving said bar rearwardly on its rockers 26, so as to free the escapement wheel 23 from the dog 22 and hold it by the usual solid dog 27. At 15 this time no movement of the typewriter carriage takes place. On the return stroke of the type-bar, the dog 22 reengages the escapement wheel, having in the meantime been drawn to the left, so that it now feeds the escapement wheel 23 along one tooth, and allows the pinion 28, connected thereto, to revolve to the same extent, thus feeding 20 the carriage along one space, because the carriage is controlled by the usual rack 29 meshing with the pinion 28.

In the computing zone, the numeral keys not only print and feed along the carriage in the manner described, but they are also 30 adapted to register the digits written, by depressing pins 30 upon pin bars 31, there being a separate bar 31 for each denomination and a separate pin 30 on each pin bar 31 for each digit key. In order to effect 35 this and to accomplish the setting of the pins 30 upon the proper pin bars, each pin bar 31 is normally drawn rearwardly by means of a spring, not shown, so that its pins normally stand out of alinement with 40 pin-setting bars 32. Inside the adding zone, however, the pin bars 31 are moved slightly forwardly, one bar at a time, to bring their pins into line with the pin-setting bars 32, so that when any numeral key 11 is de- 45 pressed, its pendant 33, in descending, will strike the usual rock arm 34 and will cause the pin-setting bar 32, connected thereto, to set the proper digit pin upon the pin bar brought to setting position.

50 To bring the pin bars to setting position, there is provided upon the carriage one or more settable dogs 35 adapted to ride *seriatim* under the front ends of jacks 36, thus depressing the rear ends 37 of the jacks to 55 carry down rods 38, with the result that each rod, when depressed, will move its pin bar 31 to setting position. The connections between the pin bars and the rods 38 may be of a usual form, which includes bell- 60 cranks 39, there being one bell-crank for each rod 38, each bell-crank engaging a transposition member 40, so that when a bell-crank 39 is rocked the transposition member rises and rocks a small bell-crank 65 41 having an arm 42 lying against a pin 43

on its pin bar, so that at the rising of the transposition member 40 the pin bar is moved forward.

When a number of pins have thus been set up to represent the digits in a number, the 70 digits represented are carried into the computing wheels 44 by drawing on the usual general-operator handle 45, which, by means of the usual connections, causes the general operator, comprising a cross-bar 46, to come 75 forward and strike the projecting ends of the pins, and carry the pin bars 31 forward to an extent dependent on the position of the pins depressed, so that the usual rack 47 on each pin bar will turn its computing 80 wheel to a corresponding extent. Upon the return movement of the handle 45, the pin bars 31 are returned to normal position by lugs 48 against which the cross-bar 46 strikes. The pins are returned to normal 85 position by the usual pin-restoring devices, not shown herein, but one form of which is disclosed in the patent to Hanson, No. 1,278,812, dated September 10, 1918.

In order to effect subtraction, there is provided a subtraction key 49, which, when pushed rearwardly, is adapted to shift the mechanism in such a way that the numeral keys 11, when depressed, instead of setting up the digit pins 30 to drive the rack bars 90 47 an amount proportional to the keys depressed, will depress pins adapted to drive the rack bars a complemental amount. To enable this to be done when the subtraction key 49 is pushed rearwardly, its rod 50, 100 which is pivoted to a long rock arm 51, rocks a subtraction dog shaft 52, so as to carry a subtraction dog 53 to ineffective position clear of the notch 54, by which the dog normally holds a subtraction-setting 105 bar 55 against the tension of a spring 56. When the dog 53 releases the bar 55, so that the spring 56 can draw it rearwardly, the bar shifts the usual rock shafts 57 by which the rock arms 34 operate the setting bars or 110 linkages 32 in the usual manner, thereby moving addition rock arms 58 clear of the addition wrists, by which the linkages are normally actuated and, at the same time, moving the subtraction rock arms 59 to engage with subtraction wrists 60, the two sets of wrists and arms being so arranged that when the rock shafts 57 are thus shifted, the numeral keys 11 will be effective on complementary linkages 32, and therefore 115 set complementary pins 30.

The connection between the subtraction bar 55 and the shafts 57 may be of the usual form, which includes a rocking plate 61 adapted to be swung around its pivot 62, 120 by means of a bell crank 63 engaging a pivot 64 upon the bar 55. In addition, the usual connections (not shown) set all the "9" pins 30 at the actuation of the subtraction-setting bar 55. In addition, the setting of the 125 130

subtraction bar 55 makes a "9" pin-restoring bar 65 effective in the usual manner. One form of the above and other connections is shown in the aforesaid patent 5 1,278,812.

According to the present invention, in addition to setting the mechanism to subtraction, the actuation of the subtraction key may be effective to change the character 10 of the printing. In the present disclosure, this change in the printing is illustrated as being effected by changing the case in which the type-heads 67 print upon the type-bars 15. To effect this, the usual case-shift mechanism of the Underwood typewriting machine may be utilized, which includes the shift carriage 19, having the usual roll 68 running upon the usual shift rail 69 in such a way that when the rail 69 is raised, the 20 platen is lifted to cause upper-case types 70 to print upon a work-sheet instead of the lower-case types 16, which normally print thereupon. In order to shift the rail 69, it may form a part of the usual shift 25 frame, which includes bell-crank ends 72 and a connecting cross-bar 73, each bell-crank end having a downwardly-extending arm 74 behind which lies an upwardly-extending arm 75 on a shift-key lever 76, with the result that when the shift-key lever 76 is depressed, the shift rail 69 is raised.

In order to effect the depression of the shift lever 76 at the actuation of the subtraction rod 50, there may be provided 30 upon the subtraction rod a pin 77 lying in front of a lower arm 78 of a bell crank 79, which is pivoted at 80, upon the framework of the typewriter. Whenever the subtraction key 49 is pushed rearwardly, to carry 40 its rod rearwardly, the bell crank 79 swings down, carrying down a pin 81 fast upon the shift lever 76 near the shift key 82, with the result that the lever 76 moves downward and the shift rail 69 moves upward.

45 In order to compel the typist when entering a subtraction zone to actuate the subtraction key 49, there may be provided a suitable tappet 83 settable upon the typewriter carriage, and adapted to lock the 50 numeral keys upon entering the subtraction zone. This tappet 83 is herein shown as a column-stop settable on the usual column-stop bar 84 and provided with an extension 55, which, at the moment the typewriter carriage enters a subtraction zone, is adapted to strike a cam 86, preferably of the length of the subtraction zone, with the result that the cam 86 is depressed to lock the numeral keys by carrying a locking bail 60 87 under suitable hooks 88 upon the numeral key levers. The connections for accomplishing this include a rod 88^a upon which the cam 86 is mounted, said rod passing through a guide-plate 89 and ex- 65 tending downwardly to a rock arm 90, upon

a rock shaft 91. Whenever the tappet 83 strikes the cam 86 it rocks the rock arm 90 against the tension of the spring 92, and rocks the shaft 91 to rock a second rock arm 93, fast thereon, forwardly, thereby 70 thrusting forwardly a thrust link 94, which is pivotally attached to the rock arm 93 and to an arm 95, upon which the locking bail 87 is mounted. This locks the numeral keys, so that they stay locked until the 75 tappet 83 passes out of the subtraction zone, when it clears the cam, and allows the spring 92 to draw the link 94 rearwardly; and then a spring 96 swings the locking bail 87 rearwardly, thus unlocking the keys. 80

To unlock the keys when the typist depresses the subtraction key 49, there may be provided a lug 97 upon the subtraction key rod 50. Said lug, when pushed rearwardly, is adapted to strike a pin 98 upon 85 a collar 99, fast upon the front part 100 of the thrust link 94. When the subtraction key is thus depressed, it carries the bail 87 rearwardly because the part 100 of the thrust link is slideable rearwardly on the 90 rest of the thrust link, since it is connected thereto by means of a spring 101 lying within a bore 102 of the thrust link 94, against which spring the end 103 of the part 100 bears. In order to limit the travel 95 of the part 100 relatively to the rest of the link 94, the part 100 may be provided with a pin 104 working in a slot 105 of suitable length to limit its throw.

The mechanism may include the usual 110 decimal-tabulating counter-stops 106, which are diagrammatically illustrated herein, and which serve to release and arrest the carriage at the proper point by co-operating with the column-stop 83.

105 During most of the travel of the carriage, the denomination-selecting dog 35 stands considerably below the jacks 36, and is only brought up to effective position in the computing zone, there being provided to 110 effect this a usual silencing roll 107, journaled upon arms 108, which are pivotally mounted at 109, so that a spring 110 may normally hold the silencing roll 107 in effective position. When the roll 107 is thus 115 held in effective position, the dog 35 is raised into effective position when entering the computing zone, since it is mounted upon a swinging block 111, so that it can swing around a rod 112 when its spool 113 120 engages the silencing roll 107.

The silencing roll may be set to ineffective position against the tension of its spring 110, there being provided for this purpose a silencing or non-add key 114, 125 which is mounted on the front end of a long push-rod 115, and, when pushed rearwardly, carries rearwardly the long rock arm 116 of a rock shaft 117, to which it is pivoted at 118, so that a follower 119, also 130

fast on the shaft 117, lifts an arm 120 on the roll-supporting arm 108, with the result that the roll 107 is swung rearwardly to ineffective position. In addition to swinging the silencing roll 107 to ineffective position, the non-add key 114 may be also adapted to make the locking bail 87 ineffective, to enable typewriting to be done with numeral keys, even in a computing zone, if desired, 10 on work which does not involve any computing. To accomplish this, the rod 115 is provided with an upright lug 121, which lies in front of a pin 122 on a rock arm 123, fast to a transverse shaft 124, so that when 15 the non-add key 114 is pushed rearwardly, it will rock the shaft 124, to cause a second rock arm 125 thereon to push rearwardly the pin 98, thus swinging the bail 87 to ineffective position. The rock shaft 124 is 20 herein illustrated, for convenience, as journaled in ears 126 upon the cover plate 127 between the computing mechanism and the typewriting mechanism.

In order to enable the non-add key 114 to be held in its rearward position, in which it holds the machine set for typewriting only, the rod 115 may be provided with a pin 128 riding in a slot 129, which has an L 130, in which the pin 128 is adapted to 25 catch and be held when at the rearward limit of its movement. In order to release the non-add key, it is merely necessary to lift it while pushing in, in order to free the pin 128 from any slight overhanging 30 in the L 130, in which the pin may be held by the action of the spring 110.

It will be noted that there is no need for any such slot for the subtraction key 49, since when that key is pushed rearwardly, 35 the dog 53 is caught under the bottom of the bar 55, as clearly shown in Fig. 3, in which position it remains until the general operator 46 comes forward and releases the subtraction setting by drawing on the subtraction bar 55 when it strikes the lug 131 on said bar. This draws the bar 55 forward 40 and permits the dog 53 to be made effective by its returning spring, shown diagrammatically at 132.

50 Variations may be resorted to within the scope of the invention, and portions of the improvements may be used without others.

Having thus described my invention, I claim:

55 1. In a combined typewriting and computing machine, the combination with typewriter numeral keys and a traveling carriage, of a device for locking said keys, a cam of limited length, a follower adapted to strike 60 said cam and be effective throughout the length of said cam, a plunger connected to the cam for making the locking device effective, said plunger comprising ends having a limited longitudinal movement with re-

spect to each other, a spring acting on the 65 ends of said plunger so as to urge said ends apart and normally hold the plunger extended, computing devices, a subtraction key, and a connection whereby when the subtraction key is actuated the plunger is 70 compressed to release the locking device.

2. In a combined typewriting and computing machine the combination with typewriter numeral keys and a traveling carriage, of a cam of limited length, a follower 75 adapted to strike said cam, a normally ineffective locking device for said numeral keys, a connection whereby said follower and said cam, while in contact with each other, hold said locking device effective, 80 computing devices, a subtraction key, and means whereby the actuation of the subtraction key makes the locking device ineffective irrespective of the position of the cam and the follower. 85

3. In a combined typewriting and computing machine, the combination with typewriter numeral keys and a traveling carriage, of a cam of limited length, a follower adapted to strike said cam, a normally ineffective locking device for said numeral keys, a connection whereby said follower and said cam, while in contact with each other, hold said locking device effective, 90 computing devices, a subtraction key, means whereby the actuation of the subtraction key makes the locking device ineffective irrespective of the position of the cam and the follower, connections between the computing devices and the subtraction 95 key whereby the subtraction key remains set, devices forming part of the computing devices on which the digits written by the keys are set up, a general operator also forming part of the computing devices, 100 computing wheels into which the general operator carries the digits set up, and a connection whereby the general operator effects the return of the subtraction key to normal position to permit the locking 105 device to come under the control of the cam and the follower. 110

4. In a combined typewriting and computing machine, the combination with typewriter numeral keys and a traveling carriage, 115 of locking devices for said keys, a cam made effective by said carriage means, actuated by said cam to make the locking devices effective, a non-compute key, and means, actuated by said non-compute key, 120 for making the cam actuated means ineffective on said locking devices.

5. In a combined typewriting and computing machine, the combination with typewriter numeral keys and a traveling carriage, 125 of locking devices for said keys, a cam made effective by said carriage means, actuated by said cam to make the locking

devices effective, a non-compute key, means, actuated by said non-compute key, for making the cam-actuated means ineffective on said locking devices, and a subtraction key 5 adapted to make the cam-actuated means ineffective on said locking devices.

6. In a combined typewriting and computing machine, the combination with typewriter numeral keys and a traveling carriage, of locking devices for said keys, a cam made effective by said carriage means, actuated by said cam to make the locking devices effective, a non-compute key, means, actuated by said non-compute key, for making the cam-actuated means ineffective on said locking devices, a subtraction key adapted to make the cam-actuated means ineffective on said locking devices, connections whereby the subtraction key when 15 made effective remains effective to the end of the computing zone, and connections whereby the completion of a computation releases the subtraction key.

7. In a machine of the class described, the combination with a traveling carriage and a tappet thereon, of a cam adapted to be depressed by said tappet over a column of substantial width, typewriter keys, a bail for locking said keys, a train of connections 30 between said bail and said cam, and a spring forming part of said train to enable the bail to be moved independently of the cam.

8. In a machine of the class described, the combination with a traveling carriage and a tappet thereon, of a cam adapted to be depressed by said tappet over a column of substantial width, typewriter numeral keys, a bail for locking said keys, a train 35 of connections between said bail and said cam including a composite rod, a spring connection forming part of said rod to enable the bail to be moved independently of the cam, and computing devices including a depressible subtraction key, a subtraction bar adapted to be released by said key, a dog by which the key holds the bar, said bar comprising a portion adapted to hold the dog to hold the key depressed and a general operator also forming part of said computing devices adapted to restore said subtraction 40 bar to release the subtraction key.

9. In a combined typewriting and computing machine, the combination with typewriter numeral keys and a traveling carriage, of a device for locking said keys, a cam of limited length, a follower adapted to strike said cam and be effective throughout the length of said cam, a plunger connected to the cam for making the locking device effective, said plunger comprising ends having a limited longitudinal movement with respect to each other, a spring acting on the ends of said plunger, so as to 55 urge said ends apart and normally hold the

plunger extended, computing devices, a subtraction key, a connection whereby when the subtraction key is actuated the plunger is compressed to release the locking device, double-case types operable by said keys, and 70 a connection whereby the subtraction key, when effective, makes the normally ineffective case of the types effective to print.

10. In a combined typewriting and computing machine, the combination with typewriter numeral keys and a traveling carriage, of a cam of limited length, a follower adapted to strike said cam, a normally ineffective locking device for said numeral keys, a connection whereby said follower 80 and said cam, while in contact with each other, hold said locking device effective, computing devices, a subtraction key, means whereby the actuation of the subtraction key makes the locking device ineffective irrespective of the position of the cam and the follower, double-case types operable by said keys, and a connection whereby the subtraction key, when effective, makes the normally ineffective case of the types effective 85 to print.

11. In a combined typewriting and computing machine, the combination with typewriter numeral keys and a traveling carriage, of a cam of limited length, a follower 95 adapted to strike said cam, a normally ineffective locking device for said numeral keys, a connection whereby said follower and said cam, while in contact with each other, hold said locking device effective, computing devices, a subtraction key, means whereby the actuation of the subtraction key makes the locking device ineffective irrespective of the position of the cam and the follower, connections between the computing devices and the subtraction key whereby the subtraction key remains set, devices forming part of the computing devices on which the digits written by the keys are set 100 up, a general operator also forming part 105 of the computing devices, computing wheels into which the general operator carries the digits set up, a connection whereby the general operator effects the return of the subtraction key to normal position to permit the locking device to come under the control of the cam and the follower, double-case types operable by said keys, and a connection whereby the subtraction key, when 110 effective, makes the normally ineffective case 115 of the types effective to print.

12. In a combined typewriting and computing machine, the combination with typewriter numeral keys and a traveling carriage, of locking devices for said keys, a cam made effective by said carriage, means actuated by said cam, to make the locking devices effective, a non-compute key, means, actuated by said non-compute key, for making the cam ineffective on said locking de- 120 125 130

5 vices, a subtraction key adapted to make the cam ineffective on said locking devices, double-case types operable by said keys, and a connection whereby the subtraction key, when effective, makes the normally ineffective case of the types effective to print.

13. In a combined typewriting and computing machine, the combination with typewriter numeral keys and a traveling carriage, of locking devices for said keys, a cam made effective by said carriage, means, actuated by said cam, to make the locking devices effective, a non-compute key, means, actuated by said non-compute key, for making the cam ineffective on said locking devices, a subtraction key adapted to make the cam ineffective on said locking devices, connections whereby the subtraction key when made effective remains effective to the

20 end of the computing zone, connections whereby the completion of a computation releases the subtraction key, double-case types operable by said keys, and a connection whereby the subtraction key, when effective, makes the normally ineffective case of the types effective to print.

14. In a combined typewriting and computing machine, the combination with typewriter numeral keys and a traveling carriage, of upper and lower case types operable by said keys, a platen against which said keys print, means for shifting the position of said platen to alter the case, computing devices, a subtraction key for said computing devices, connections whereby said subtraction key operates said platen-shifting means, and a carriage-controlled lock for the numeral keys, adapted to be released by the operation of said subtraction

40 key.

15. In a combined typewriting and computing machine, the combination with typewriter numeral keys and a traveling carriage, of upper and lower case types operable by said keys, a platen against which said keys print, means for shifting the position of said platen to alter the case, computing devices, a subtraction key for said computing devices, connections whereby said subtraction key operates said platen-shift means, a carriage-controlled lock for the numeral keys, adapted to be released by the operation of said subtraction key, connections, included in said devices, for holding said platen-shift means effective throughout the computing zone, and means whereby the completion of a computation releases said platen-shift means.

16. In a machine of the class described, the combination with a subtraction key and a case-shift key, of a connection whereby the subtraction key operates the case-shift key, typewriter numeral keys, a lock for said numeral keys, a carriage control for said lock, and a connection for releasing

said lock by operation of the subtraction key.

17. In a combined typewriting and computing machine, the combination with typewriter numeral keys and a traveling carriage, of printing devices for printing in upper and lower case, operable by said keys, case-shift devices, computing devices, a subtraction key for said computing devices adapted to operate said case-shift devices, a lock for said numeral keys, said carriage controlling said lock, and a connection whereby the operation of the subtraction key releases the lock.

18. In a combined typewriting and computing machine, the combination with typewriter numeral keys and a traveling carriage, of printing devices for printing in upper and lower case, operable by said keys, case-shift devices, computing devices, a subtraction key for said computing devices adapted to operate said case-shift devices, a lock for said numeral keys, said carriage controlling said lock, a connection whereby the operation of the subtraction key releases the lock, a subtraction bar for holding said subtraction key effective, and means for returning said subtraction bar to normal position at the close of a computation.

19. In a combined typewriting and computing machine, the combination with typewriter numeral keys and a traveling carriage, of printing devices for printing in upper and lower case, operable by said keys, case-shift devices, computing devices, a subtraction key for said computing devices adapted to operate said case-shift devices, a lock for said numeral keys, said carriage controlling said lock, a connection whereby the operation of the subtraction key releases the lock, and a carriage-controlled cam, extending some distance along the travel of said carriage, forming lock-operating means.

20. In a combined typewriting and computing machine, the combination with typewriter numeral keys and a traveling carriage, of printing devices for printing in upper and lower case, operable by said keys, case-shift devices, computing devices, a subtraction key for said computing devices adapted to operate said case-shift devices, a lock for said numeral keys, said carriage controlling said lock, a connection whereby the operation of the subtraction key releases the lock, a subtraction bar for holding said subtraction key effective, means for returning said subtraction bar to normal position at the close of a computation, and a carriage-controlled cam, extending some distance along the travel of said carriage, forming lock-operating means.

21. In a machine of the class described, the combination with a traveling carriage and a tappet thereon, of computing devices,

- 5 a cam adapted to be depressed by said tappet over a column of substantial width, typewriter numeral keys, a bail for locking said keys, a train of connections between said bail and said cam, including a composite rod having a spring connection forming part thereof to enable the bail to be moved independently of the cam, and a subtraction key for so moving said bail.
- 10 22. In a machine of the class described, the combination with a traveling carriage and a tappet thereon, of computing devices, a cam adapted to be depressed by said tappet over a column of substantial width, typewriter numeral keys, a bail for locking said keys, a train of connections between said bail and said cam, including a composite rod having a spring connection forming part thereof to enable the bail to be moved independently of the cam, and a non-add key for so moving said bail.
- 15 23. In a combined typewriting and computing machine, the combination with typewriter numeral keys and a traveling carriage, of a device for locking said keys, a cam of limited length, a follower adapted to strike said cam and be effective throughout the length of said cam, a plunger connected to the cam for making the locking device effective, said plunger comprising ends having a limited longitudinal movement with respect to each other, a spring acting on the ends of said plunger, so as to urge said ends apart and normally hold the plunger extended, computing devices, a subtraction key, a connection whereby when the subtraction key is actuated the plunger is compressed to release the locking device, double-case types operable by said keys, a connection whereby the subtraction key, when effective, makes the normally ineffective case of the types effective to print, and a non-add key adapted to release the locking device independently of the subtraction key.
- 20 24. In a combined typewriting and computing machine, the combination with typewriter numeral keys and a traveling carriage, of a cam of limited length, a follower adapted to strike said cam, a normally ineffective locking device for said numeral keys, a connection whereby said follower and said cam, while in contact with each other, hold said locking device effective, computing devices, a subtraction key, means whereby the actuation of the subtraction key makes the locking device ineffective irrespective of the position of the cam and the follower, double-case types operable by said keys, a connection whereby the subtraction key, when effective, makes the normally ineffective case of the types effective to print, and a non-add key adapted to release the locking device independently of the subtraction key.
- 25 25. In a combined typewriting and computing machine, the combination with typewriter numeral keys and a traveling carriage, of upper and lower-case types operable by said keys, a platen against which said keys print, means for shifting the position of said platen to alter the case, computing devices, a subtraction key for said computing devices, connections whereby said subtraction key operates said platen-shifting means, a carriage-controlled lock for the numeral keys adapted to be released by the operation of said subtraction key, a non-compute key, and a connection whereby the non-compute key releases said lock.
- 30 26. In a combined typewriting and computing machine, the combination with typewriter numeral keys, and a traveling carriage, of upper and lower-case types operable by said keys, a platen against which said keys print, a case-shift key for altering the position of said platen to alter the case, computing devices, a subtraction key for said computing devices, connections whereby said subtraction key operates the case-shift key, a carriage-controlled lock for the numeral keys adapted to be released by the operation of said subtraction key, connections included in said devices for holding the case-shift key effective throughout the computing zone, means whereby the completion of a computation releases the case-shift key, a non-add key, and a connection whereby the non-add key makes said lock ineffective.
- 35 27. In a machine of the class described, the combination with a subtraction key and a case-shift key, of a connection whereby the subtraction key operates the case-shift key, typewriter numeral keys, a lock for said numeral keys, a carriage control for said lock, a connection for releasing said lock by operation of the subtraction key, a non-add key, and a connection whereby said non-add key makes the lock ineffective.
- 40 28. In a combined typewriting and computing machine, the combination with typewriter numeral keys and a traveling carriage, of printing devices for printing in upper and lower-case operable by said keys, case-shift devices, computing devices, a subtraction key for said computing devices adapted to operate said case-shift devices, a lock for said numeral keys, said carriage controlling said lock, a connection whereby the operation of the subtraction key releases the lock, a non-add key, and a connection whereby said non-add key makes the lock ineffective.
- 45 29. In a combined typewriting and computing machine, the combination with typewriter numeral keys and a traveling carriage, of printing devices for printing in upper and lower-case operable by said keys, case-shift devices, computing devices, a sub-

- traction key for said computing devices adapted to operate said case-shift devices, a lock for said numeral keys, said carriage controlling said lock, a connection whereby the operation of the subtraction key releases the lock, a subtraction bar for holding said subtraction key effective, means for returning said subtraction bar to normal position at the close of a computation, a non-add key, and a connection whereby said non-add key makes the lock ineffective.
30. In a combined typewriting and computing machine, the combination with typewriter numeral keys and a traveling carriage, of printing devices for printing in upper and lower-case operable by said keys, case-shift devices, computing devices, a subtraction key for said computing devices adapted to operate said case-shift devices, a lock for said numeral keys, said carriage controlling said lock, a connection whereby the operation of the subtraction key releases the lock, a carriage-controlled cam extending some distance along the travel of said carriage forming lock-operating means, and a non-add key adapted to make the cam ineffective to operate the lock.
31. In a combined typewriting and computing machine, the combination with typewriter numeral keys and a traveling carriage, of printing devices for printing in upper and lower case operable by said keys, case-shift devices, computing devices, a subtraction key for said computing devices adapted to operate said case-shift devices, a lock for said numeral keys, a connection whereby the operation of the subtraction key releases the lock, a cam extending some distance along the travel of said carriage forming lock-operating means, an adjustable cam-operating tappet on the carriage, and means for making the cam ineffective at will.
32. In a machine of the class described, the combination with a subtraction key and a case-shift key, of a connection whereby the subtraction key operates the case-shift key, typewriter numeral keys, a bail for locking said numeral keys, a carriage control for making said bail effective, and a lug on the subtraction key for releasing said bail by operation of the subtraction key.
33. In a combined typewriting and computing machine, the combination with typewriter numeral keys and a traveling carriage, of a swinging bail for locking said keys, a cam of limited length, a follower adapted to strike said cam and be effective throughout the length of said cam, a plunger connected to the cam for making the bail effective, said plunger comprising ends having a limited longitudinal movement with respect to each other, a spring acting on the ends of said plunger so as to urge said ends apart and normally hold the plunger

extended; computing devices, a subtraction key, and a lug on the subtraction key adapted to compress the plunger to swing the bail to release the keys.

34. In a combined typewriting and computing machine, the combination with typewriter numeral keys and a traveling carriage, of a swinging bail for locking said keys, a cam of limited length, a follower adapted to strike said cam and be effective throughout the length of said cam, a plunger connected to the cam for making the bail effective, said plunger comprising ends having a limited longitudinal movement with respect to each other, a spring acting on the ends of said plunger so as to urge said ends apart and normally hold the plunger extended, computing devices, a subtraction key, a lug on the subtraction key adapted to compress the plunger to swing the bail to release the keys, and a non-compute key comprising a lug also adapted to release the keys.

35. In a combined typewriting and computing machine, the combination with typewriter numeral keys and a traveling carriage, of a device for locking said keys, a primary member mounted on the carriage, a secondary member yieldably supported in the path of said primary member, said members being so shaped that the secondary member, upon engagement by the primary member, will be shifted to a predetermined position and there maintained while passing through a computing zone, a train of connections between said secondary member and said locking device whereby the latter may be rendered effective by the former, said train of connections including a yieldable element, a subtraction key, and means whereby actuation of said subtraction key will overcome said yieldable element and render said locking device ineffective.

36. In a combined typewriting and computing machine, the combination with typewriter numeral keys and a traveling carriage, of a cam of substantially the length of a computing zone, a follower adapted to strike said cam, a normally ineffective locking device for said numeral keys, a connection whereby said follower and said cam, while in contact with each other, hold said locking device effective, said connection comprising a yieldable element, a subtraction key, and means whereby actuation of the subtraction key will overcome said yieldable element and render the locking device ineffective.

37. In a combined typewriting and computing machine, the combination with a traveling carriage, of typewriter keys provided with hooks, a bail to coöperate with said hooks to lock said keys, said bail being normally in ineffective position, a link connected with said bail, carriage-actuated

- means effective, while passing through a computing zone, to yieldingly urge said link to move said bail to effective position, a stud projecting from said link, and a subtraction key having a projection adapted to engage said stud, so that depression of said subtraction key will actuate said stud and thereby move said link and consequently the bail to ineffective position.
- 5 38. In a combined typewriting and computing machine, the combination with a traveling carriage, of typewriter keys provided with hooks, a bail to coöperate with said hooks to lock said keys, said bail being normally in ineffective position, a link connected with said bail, carriage-actuated means effective, while passing through a computing zone, to yieldingly urge said link to move said bail to effective position, a stud projecting from said link, a subtraction key 20 having a finger adapted to engage said stud, so that depression of said subtraction key will actuate said stud and thereby move said link and consequently the bail to ineffective position, a second finger to engage said stud, a non-compute key, and means whereby said non-compute key, when depressed, will actuate said second finger so as to move said bail to ineffective position.
- 10 15. 38. In a combined typewriting and computing machine, the combination with a traveling carriage, of typewriter keys provided with hooks, a bail to coöperate with said hooks to lock said keys, said bail being normally in ineffective position, a link connected with said bail, carriage-actuated means effective, while passing through a
